UNITED STATES PATENT OFFICE.

JOSEPH P. SCROGGS, OF INDIANAPOLIS, INDIANA.

DESIGN FOR A CONDIMENT RECEPTACLE.

Application filed April 12, 1929. Serial No. 30,857. Term of patent 7 years.

To all whom it may concern:

Be it known that I, JOSEPH P. SCROGGS, a citizen of the United States, residing at Indianapolis, Marion County, Indiana, have invented a new, original, and ornamental Design for Condiment Receptacle, of which the following is a specification, reference being had to the accompanying drawing, forming part thereof.

I claim:

The ornamental design for a condiment receptacle, as shown.

JOSEPH P. SCROGGS.
